DESIGN FOR A BOX COVER

Martha Hallowell Connor, Baltimore, Md., assignor to The Tin Decorating Company of Baltimore, Baltimore, Md., a corporation of
New Jersey

Application February 8, 1935, Serial No. 55,320

Term of patent 14 years

To all whom it may concern:

Be it known that I, Martha Hallowell Connor, a citizen of the United States, residing in the city of Baltimore, State of Maryland, have invented a new, original, and ornamental Design for a Box-Cover, of which the following is a specification, reference being had to the accompanying drawing, forming a part thereof, wherein—

Fig. 2 is a side view thereof, partly in section.

What I claim is:

The ornamental design for a box cover, as shown.

MARTHA HALLOWELL CONNOR.
